UNITED STATES PATENT OFFICE.

FREDERIC PAUL IMPEY, OF BIRMINGHAM, ENGLAND, ASSIGNOR TO HARRY F. BUSHONG,
OF KALAMAZOO, MICHIGAN.

TEMPORARY BINDER.

No. 920,146.

Specification of Letters Patent.

Patented May 4, 1909.

Application filed January 18, 1908. Serial No. 411,520.

To all whom it may concern:

Be it known that I, FREDERIC PAUL IMPEY, a subject of the King of Great Britain, residing at Birmingham, county of Warwick, England, have invented certain new and useful Improvements in Temporary Binders, of which the following is a specification, for which application has been made in Great Britain, No. 27,195, dated November 29, 10 1906.

This invention relates to improvements in binders.

The main objects of this invention are: First, to provide in a binder an improved locking mechanism, whereby the removal or inspection of the leaves is prevented. Second, to provide in a temporary binder an improved locking mechanism adapted to accomplish both of the results above specified 20 by a single lock; and third, to provide an improved locking mechanism for temporary binders by which the adjustment of the binder mechanism and the inspection of the sheets or leaves contained therein are prevented, which is very simple and economical 25 in structure and may be very easily manipulated.

Further objects, and objects relating to structural details, will definitely appear from 30 the detailed description to follow.

I accomplish the objects of my invention by the devices and means described in the following specification.

The invention is clearly defined and 35 pointed out in the claims.

A structure embodying the features of my invention is clearly illustrated in the accompanying drawing, forming a part of this specification, in which--

40 Figure 1 is a detail inside view of a structure embodying the features of my invention, the book being shown open, the leaves being conventionally shown in an upright position, and parts of the covers being broken away to 45 better show the structural details; Fig. 2 is a longitudinal section through the structure shown in Fig. 1, in its closed and locked position, the view being taken on a line corresponding to line 2—2 of Fig. 1; Fig. 3 is an 50 enlarged detail section, taken on a line corresponding to line 3—3 of Fig. 1, showing structural details of the means for connecting the cover securing strap to one of the covers; and Fig. 4 is a detail, showing the arrangement of

the escutcheon for the lock on one part of the 55 covers.

In the drawing, similar numerals of reference refer to similar parts throughout the several views, and the sectional views are taken looking in the direction of the little arrows at the ends of the section lines.

I have in the accompanying drawing shown my invention as embodied in a temporary binder, substantially such as is illustrated and described in United States Letters Patent to Harry F. Bushong, No. 851,276, issued April 23, 1907, as that is the structure to which I have applied it in use. I desire to remark, however, and it is obvious to one skilled in the art that it might be applied to various other structures, and I desire to be understood as not limiting myself to the particular embodiment of my invention which I have shown for illustrative purposes.

75 Referring to the drawing, the covers 1 are preferably chambered to receive the binding mechanism. The clamping bars 2 for the leaves or sheets, as 3, are preferably secured to the inner ends of the covers by means of suitable hinges, as 4. As the details of this connection form no part of this invention, they are not here illustrated. The binding cords 5 are preferably formed of one piece, being arranged through the inner ends of the 80 covers and clamping bars and passed about the bearing block in one cover and connected to the cross bar 7 arranged in the chamber of the other cover. This cross bar is adjusted by means of the screw 8, which is mounted 85 in suitable bearings 9 and 10 in the cover, the screw being adapted to be manipulated by means of a key from without the cover, the cover being provided with a key opening 11, as clearly appears from the drawing. 90 These features of the binder which I have shown more or less in conventional form are, as stated, preferably those illustrated in the 95 patent hereinbefore referred to.

Within the cover chamber containing the 100 adjusting mechanism, I arrange a lock 12, the bolt 13 of which is adapted, when shot, to close the key opening 11, thereby preventing the manipulation of the binder adjusting mechanism. The escutcheon 14 of the 105 lock is located so that it can be manipulated from the outside of the binder.

As it is sometimes desirable to prevent the

inspection of the leaves, as well as to prevent their removal from the binder, I provide means for securing the covers in their closed position. This preferably consists of a strap 5 15, which is adjustably secured to one of the covers by means of the buckle 16. This buckle is arranged on the inside of the cover, and is provided with a pivoted tongue 17, having a finger piece 18 which projects inwardly when the tongue is in its engaging position, so that, when the book is closed, the finger piece is engaged by the sheets or leaves, as clearly appears in Fig. 2, so that it is impossible to lift the same with the book 10 closed and the strap secured to the opposite cover. The tongue members 17 of the buckle are preferably curved and adapted to pass through openings 19 formed therefor in the inner wall of the cover, thus preventing any 15 manipulation from the outside of the book, slipping the straps over the ends of the tongues, or bending the tongues to permit the withdrawal of the strap without such force being used as would permanently destroy the mechanism. The strap 15 is provided with a bolt-engaging member 20, which is adapted to be inserted in the key hole opening 11 of the opposite cover, as clearly appears in Fig. 2, thus closing the 20 opening, thereby further adding to the security of the device.

It is obvious that my improved locking mechanism is very simple and it is at the same time very secure and convenient in use. 35 The cover securing strap may be adjusted to correspond with the adjustment of the leaf binding mechanism, so that the hook is adapted for the securing of any desired number of sheets, and, at the same time effectively locked to prevent removal or the inspection of the leaves.

I have, as previously remarked, illustrated and described my invention in detail in the form preferred by me and I desire to here remark that I am aware that it is capable of very great variation in structural details 45 without departing from my invention.

Having thus described my invention, what I claim as new and desire to secure by Letters Patent is:

1. In a temporary binder or loose sheet holder, the combination with the covers, one of which is chambered, said chambered cover having a key opening therein; a binding 55 mechanism; a key - operated adjusting means therefor arranged in said chambered cover; a lock arranged within said chambered cover, so that its bolt, when shot, closes the said key opening thereof; a strap; a bolt-engaging member adapted to be inserted in said key opening of said cover secured to said strap; a buckle arranged upon the inside of the other cover for adjustably securing said strap thereto, said buckle having a pivoted curved tongue, adapted to pass

into the inner wall of the cover; and a finger piece for said tongue adapted to project inwardly when said tongue is in its engaging position.

2. In a temporary binder or loose sheet holder, the combination with the covers, one of which is chambered, said chambered cover having a key opening therein; a binding mechanism; a key - operated adjusting means therefor arranged in said chambered cover; a lock arranged within said chambered cover, so that its bolt, when shot, closes the said key opening thereof; a strap; a bolt-engaging member adapted to be inserted in said key opening of said cover secured to said strap; and a buckle arranged upon the inside of the other cover for adjustably securing said strap thereto, said buckle having a pivoted curved tongue adapted to pass into the inner wall of the cover.

3. In a temporary binder or loose sheet holder, the combination with the covers, one of which is chambered, said chambered cover having a key opening therein; a binding mechanism; a key - operated adjusting means therefor arranged in said chambered cover; a lock arranged within said chambered cover, so that its bolt, when shot, closes the said key opening thereof; a strap; a bolt-engaging member adapted to be inserted in said key opening of said cover secured to said strap; and means for adjustably securing the said strap to the other cover.

4. In a temporary binder or loose sheet holder, the combination with the covers, one of which is chambered, said chambered cover having a key opening therein; a binding mechanism; a key - operated adjusting means therefor arranged in said chambered cover; a lock carried by said chambered cover; a strap; a bolt-engaging member secured to said strap, said bolt-engaging member being adapted to be inserted in said opening of said cover and to close the same; a buckle arranged upon the inside of the other cover for adjustably securing said strap thereto, said buckle having a pivoted tongue adapted to pass into the inner wall of the cover when in its engaging position; and a finger piece for said tongue adapted to project inwardly when said tongue is in its engaging position.

5. In a temporary binder or loose sheet holder, the combination with the covers, one of which is chambered, said chambered cover having a key opening therein; a binding mechanism; a key - operated adjusting means therefor arranged in said chambered cover; a lock carried by said chambered cover; a strap; a bolt - engaging member being adapted to be inserted in said key opening of said cover and to close the same; and a buckle arranged upon the inside of the cover.

other cover for adjustably securing said strap thereto, said buckle having a pivoted tongue adapted to pass into the inner wall of the cover when in its engaging position.

5 6. In a temporary binder or loose sheet holder, the combination with the covers, one of which is chambered, said chambered cover having a key opening therein; a binding mechanism; a key - operated adjusting 10 means therefor arranged in said chambered cover; a lock carried by said chambered cover; a strap; a bolt-engaging member secured to said strap, said bolt-engaging member being adapted to be inserted in said key 15 opening of said cover and to close the same; and means for adjustably securing the said strap to the other cover.

7. In a temporary binder or loose sheet holder, the combination with the covers, of 20 an adjustable leaf or sheet binding means; an adjusting means therefor carried by one of said covers; a lock carried by the said cover by which said adjusting means is carried; a connecting strap for said covers; means for 25 adjustably securing said strap to the inside of the other cover; and a bolt-engaging member secured to said strap, said bolt-engaging member being adapted, when engaged with the bolt, to prevent the manipulation of said 30 binder adjusting means.

8. In a temporary binder or loose sheet holder, the combination with the covers, of an adjustable leaf or sheet binding means; an adjusting means therefor carried by one 35 of the said covers; a lock carried by the said cover by which said adjusting means is carried; a connecting strap for said covers; means for adjustably securing said strap to the other cover; and a bolt-engaging member 40 secured to said strap, said bolt-engaging member being adapted, when engaged with the bolt, to prevent the manipulation of said binder adjusting means.

9. In a temporary binder or loose sheet 45 holder, the combination with the covers, of an adjustable leaf or sheet clamping means; an adjusting means therefor carried by one of said covers; a lock carried by the said cover by which said adjusting means is carried; and means for securing said covers in 50 their closed position adjustably connected to the other cover adapted to be secured by said lock, said lock being also adapted to prevent the manipulation of said leaf binding adjusting means.

55 10. In a temporary binder or loose sheet holder, the combination with the covers, of

an adjustable leaf or sheet clamping means; an adjusting means therefor carried by one of said covers; a lock for said adjusting 60 means; and means for securing said covers in their closed position adjustably connected to the other cover adapted to be secured by said lock.

11. In a temporary binder or loose sheet 65 holder, the combination with the covers, of adjustable leaf or sheet clamping means; a strap for securing said covers in their closed position, adjustably connected to one of said covers said connection being arranged to be 70 adjusted only from the inside of the cover; and a lock for securing said strap to the other cover adapted also to prevent the adjustment of said leaf or sheet clamping means.

12. In a temporary binder or loose sheet 75 holder, the combination with the covers, of adjustable leaf or sheet clamping means; an adjustable means for securing said covers in their closed position, arranged to be adjusted only when the binder is open; and a lock for 80 securing said cover securing means adapted also to prevent the adjustment of said leaf or sheet clamping means.

13. In a temporary binder or loose sheet 85 holder, the combination with the covers, of adjustable leaf or sheet clamping means; an adjustable means for securing said covers in their closed position; and a lock for securing said cover securing means adapted also to prevent the adjustment of said leaf or sheet 90 clamping means.

14. In a temporary binder or loose sheet holder, the combination with the covers, of adjustable leaf or sheet clamping means; and an adjustable locking means for securing said 95 covers in their closed position said locking means being also arranged to lock said adjustable leaf or sheet clamping means.

15. In a temporary binder or loose leaf 100 holder, the combination with the covers, of leaf or sheet securing means and means for securing the covers in their closed position, comprising a lock, said lock being also adapted to lock the leaf or sheet securing means whereby the opening of the book and the releasing of the sheets are prevented. 105

In witness whereof, I have hereunto set my hand and seal in the presence of two witnesses.
